UNITED STATES PATENT OFFICE.

WILLIAM B. LOUTHAN, OF EAST LIVERPOOL, OHIO.

ELECTRIC HEATING UNIT.

Application filed December 21, 1926. Serial No. 156,176.

This invention relates to electric heating units and it is an object of the invention to provide a device of this kind embodying a resistance wire and a base or plate and 5 wherein the wire is applied to the base or plate in a manner to bring the wire close to the object on the base or plate to be heated.

Another object of the invention is to provide a heating unit of this kind comprising 10 a grooved base or plate in which is adapted to be positioned a resistance wire, said wire being formed with a series of folds, all of the folds being substantially coplanar.

A further object of the invention is to 15 provide a unit of this kind comprising a base or plate having a groove in which a resistance wire is adapted to be positioned, the side walls of such groove being undercut to facilitate the maintenance of the 20 resistance wire in applied or working position.

The invention consists in the details of construction and in the combination and arrangement of the several parts of my 25 improved electric heating unit whereby certain important advantages are attained and the device rendered simpler, less expensive and otherwise more convenient and advantageous for use, as will be hereinafter more 30 fully set forth.

The novel features of my invention will hereinafter be definitely claimed.

In order that my invention may be the better understood, I will now proceed to 35 describe the same with reference to the accompanying drawing, wherein:—

Figure 1 is a view in top plan of an electric heating unit constructed in accordance with an embodiment of my invention, the 40 resistance wire being shown in fragment;

Figure 2 is an enlarged fragmentary sectional view taken radially of the unit as 45 illustrated in Figure 1, the resistance wire being shown transversely flexed to facilitate its application;

Figure 3 is an enlarged fragmentary sectional view taken radially of Figure 1, showing the resistance wire in applied or working position.

As disclosed in the accompanying drawing, P denotes a plate of desired dimensions and configuration and formed of suitable 50 electric insulating material, such as porcelain. The upper surface of the plate P, or 55 base as it may be called, is herein disclosed as provided with a plurality of concentric

grooves 1 of desired width and depth with the bottom wall of each of said grooves being flattened. At this time, however, it is to be understood that these grooves may be arranged in any manner preferred and for which reason I do not wish to be understood as limiting myself to concentric grooves.

The side walls a of each of the grooves 1 have their lower portions undercut, as at 2, 60 the bottom or base walls of such undercut portions 2 being flush with the bottom wall of the groove 1 proper.

The resistance wire W comprised in my improved unit is formed with a plurality of transversely disposed folds 3, said folds being of such length to provide a resistance element of a width in excess of the width of the upper or outer portion of a groove 1 but snugly resting upon the bottom of such 75 groove and extending within the undercuts 2 when the wire or element W is in applied or working position as is illustrated in Figure 3. In applying the wire or element W the same may be readily flexed transversely 80 as indicated in Figure 2 to reduce the width of such wire or element to permit its ready application through the upper portion of the groove 1.

When the wire or element W is within 85 the lower portion of the groove said wire or element will expand for close contact with the bottom wall of the groove and this contact maintained by the marginal portions having close engagement with the side walls 90 of the undercuts 2, said side walls being inclined inwardly and outwardly as is particularly illustrated in Figure 2.

It is also to be particularly noted that the 95 folds 3 of the wire or element W are coplanar so that when in working or applied position such wire or element will have close contact with the bottom of the groove 1 in which it is applied and also the bottoms of the undercuts 2 in which the marginal portions of such wire or element extend.

With an electric heating unit constructed 100 as herein disclosed, it will be readily noted that the resistance wire or element will be effectively maintained in applied or working position yet can be readily removed or applied when desired. Furthermore, it is to be particularly noted in Figures 2 and 3 that the grooves 1 are relatively shallow so 105 that the resistance wire or element in each of such grooves will be close to the object placed upon the plate or base P to be heated.

From the foregoing description it is thought to be obvious that an electric heating unit constructed in accordance with my invention is particularly well adapted for 5 use by reason of the convenience and facility with which it may be assembled and operated, and it will also be obvious that my invention is susceptible of some change and modification without departing from the 10 principles and spirit thereof and for this reason I do not wish to be understood as limiting myself to the precise arrangement and formation of the several parts herein shown in carrying out my invention in practice except as hereinafter claimed.

I claim:

An electric heating unit comprising, in combination, an insulating member having

a groove in a surface thereof, the side walls of the groove having their lower portions undercut, the side walls of said undercuts being inclined downwardly and outwardly, and a flat resistance element extending within the groove and having close contact with the bottom thereof, said element extending within the undercuts with the marginal portions of the element in engagement with the side walls of said undercuts, said element possessing sufficient inherent resiliency to maintain the same normally flat and permitting the same to be flexed transversely for insertion within the groove.

In testimony whereof I hereunto affix my signature.

WILLIAM B. LOUTHAN.
